THRUST BALANCING APPARATUS

Ernest F. Miller, Lansdowne, Pa., assignor to Westinghouse Electric & Manufacturing Company, East Pittsburgh, Pa., a corporation of Pennsylvania

Application February 21, 1942, Serial No. 431,791

6 Claims. (Cl. 257—43)

This invention relates to means for balancing moments and reactions exerted upon relatively rigid joints between two pieces of apparatus resulting from moments produced by hydrostatic thrust in expansion joints carried by one of the pieces of apparatus, and has for an object the provision of improved thrust-balancing means for use therewith.

In certain steam condenser installations, particularly cooling tower applications, the circulating water pressure acting through expansion joints in the water supply and discharge conduits creates harmful bending moments on the joint between the condenser exhaust inlet and the turbine casing. Some of these moments tend to open the joint between the turbine and condenser and create distortion in the turbine structure while others produce a shearing action at the same location. Therefore, it is an object of this invention to provide means for counteracting or reducing the moments and reactions on the joint to a point where they have no serious effect upon the turbine-condenser joint.

These and other objects are effected by the invention as will be apparent from the following description and claims taken in accordance with the accompanying drawing, forming a part of this application, in which:

In the drawing, Fig. 1 is a side elevational view of a condenser embodying the present invention, a portion of the structure being broken away for the sake of clearness;

Fig. 2 is a transverse sectional view taken along the line II—II of Fig. 1, looking in the direction of the arrows;

Fig. 3 is a view similar to Fig. 2, with the balancing expansion element located in a slightly different position with respect to the apparatus; and,

Fig. 4 is a diagram relating to the construction illustrated in Fig. 3.

Referring now to the drawing more in detail there is shown, at 10, a condenser comprised by a shell 11 having an exhaust steam inlet 12 at the top and a condensate outlet 13 at the bottom. The condenser is connected to the underside of a turbine 14 by mating flanges 15 and 16, carried by the condenser and turbine, respectively.

A plurality of tubes 18 extend longitudinally of the shell and have their terminal portions supported by end tube plates 19. Waterbox structures 20 and 21 are associated with the tube plates 19, the waterbox 20 having a partition 22 dividing the interior thereof into an inlet chamber 23 and an outlet chamber 24, resulting

in flow of condensing water through the tubes 18 in two passes, the waterbox 21 providing a reversing chamber. The waterbox 20 is provided with inlet and outlet connections 26 and 27 which are connected, by expansion joints 28 and 28a, respectively, with water-supply and discharge conduits 29 and 30, respectively.

The structure so far described may be considered as conventional. The hydrostatic thrusts exerted on the condenser through the expansion joints 28 and 28a would, if not counteracted or balanced, produce moments and reactions on the relatively rigid joint between the condenser and turbine. In order to reduce or eliminate these reactions on the condenser-turbine joint, the present invention contemplates the provision of an expansion element 35 positioned between a rigid or fixed support 36 and the condenser waterbox 20, communication being provided between the expansion element 35 and the interior of the waterbox 20 by a conduit 37. In order that any pulsations present in the water flowing through the waterbox may be prevented from reaching the expansion element 35, the conduit 37 connecting the element with the waterbox may be provided with a restricting member or partition 38 having a relatively small opening 39 therethrough. This arrangement will permit any gradual pressure change occurring in the waterbox to be received in the expansion element 35, while preventing any rapid pressure changes such as pulsations being transmitted thereto.

In the arrangement shown in Fig. 2, the expansion element 35 has been so located as to counteract or eliminate bending moments tending to open the joint between the condenser and turbine, the moments producing shearing effect on the joint being disregarded.

By repositioning the expansion element 35 in the manner indicated in Fig. 3, the shearing effect on the joint between the condenser and turbine are eliminated, as well as the bending moments.

Selection of the proper location for the balancing expansion element 35 should involve no difficulty for one skilled in the art of condenser design. However, there is shown in Fig. 4, by way of illustration only, a method of determining the location for the expansion element of Fig. 3. In Fig. 4 the arrow OA represents the direction and magnitude of the force applied to the condenser at the expansion joint 28a and the arrow OB represents the corresponding direction and magnitude of the force exerted at the expansion joint 28. Assuming that the two forces OA and OB

are equal in magnitude, the square OA DB is determined. The diagonal OD represents the direction and magnitude of the balancing force required, it being only necessary to lay off this force as the line OC of a length equal to the diagonal OD and lying along the continuation of the diagonal OD. The point O at which the three arrows meet corresponds to the point X in Fig. 3.

While the invention has been shown in several forms, it will be obvious to those skilled in the art that it is not so limited, but is susceptible of various other changes and modifications without departing from the spirit thereof, and it is desired, therefore, that only such limitations shall be placed thereupon as are specifically set forth in the appended claims.

What is claimed is:

1. In a first device having liquid supply and discharge conduits containing expansion joints, which device is connected to a second device by a relatively rigid joint; expansion apparatus disposed between said first device and a fixed support to reduce moments and reactions on the relatively rigid joint resulting from moments produced by hydrostatic thrust in the expansion joints of the liquid supply and discharge conduits.

2. In a first device having fluid supply and discharge conduits containing expansion joints, which device is connected to a second device by a relatively rigid joint; expansion apparatus disposed between said first device and a fixed support to reduce moments and reactions on the relatively rigid joint resulting from moments produced by fluid thrust in the expansion joints of the fluid supply and discharge conduits.

3. In a first device providing a path for circulation of liquid and having liquid-supply and discharge conduits containing expansion joints, which device is connected to a second device by a relatively rigid joint; expansion apparatus disposed between the first device and stationary supporting means, and means providing communication between the expansion apparatus and the liquid circulation path provided by the first device, said expansion apparatus being so positioned with respect to the first device as to reduce moments and reactions on the relatively rigid joint

resulting from moments produced by hydrostatic thrust in the expansion joints of the liquid supply and discharge conduits.

4. In a condenser secured to a member by a relatively rigid connection; a nest of tubes; waterbox structure for directing condensing water through said tubes; water inlet and outlet connections carried by the waterbox structure; expansion joints joining said inlet and outlet connections to supply and discharge conduits; respectively; an expansion element disposed between the waterbox structure and a fixed support; and means providing communication between the expansion element and the waterbox structure, said expansion element being of such size and so positioned with respect to the waterbox inlet and outlet connections as to reduce moments and reactions on the relatively rigid connection resulting from moments produced by hydrostatic thrust in the expansion joints.

5. Structure as specified in claim 4 wherein the means providing communication between the expansion element and the waterbox structure comprises a conduit having a minimum cross sectional area that is relatively small as compared to the cross sectional area of the expansion element, whereby any pulsations present in water passing through the waterbox structure are prevented from affecting the expansion element.

6. In combination, first and second devices connected by a rigid joint, conduits for supplying fluid to and discharging fluid from the second device, at least one of the conduits including a main body portion connected by an expansion joint to a nipple joined to the second device, said nipple being so disposed that the pressure of fluid therein provides a thrust acting on the second device and on the joint between the devices, and means for applying to the second device a counter thrust opposing the effect of said first thrust on said rigid joint, said last-named means comprising a hollow structure interposed between the second device and a fixed support and including an expansion joint and means providing for the maintenance of fluid under pressure within said hollow structure.
